HACKLE FOR ARTIFICIAL FISHING FLY
AND METHOD OF MAKING SAME

George F. Grant, Butte, Mont.

Application March 27, 1939, Serial No. 264,450

2 Claims. (Cl. 43—48)

This invention relates to a hackle for artificial fishing flies and the method of making the same.

Hair which is lashed on to the shank of a hook by successive bindings of silk thread expands when wet and forces the binding. The hair dries after use and contracts while the bindings do not return to their original position, resulting in the hair becoming loose and falling out. With these disadvantages in mind it is an object of 10 the present invention to provide a method of constructing a hackle from which the hair will not pull out even after repeated use.

A further object is to produce a method of 15 constructing a hair hackle with a narrow rib or base, which is comparable in size to the quill on a feather hackle. The advantage of this is that the woven hair hackle can be used in place of a feather on any type of fly where the feather is now used, which is not true of hair that is 20 lashed to the hook with silk thread or other bindings.

It is practically impossible to apply hair to a hook by lashing it on with a flexible binding so 25 that it encircles the hook evenly at all points and will not bunch and destroy the life-like appearance of the fly. It is therefore another object of the invention to produce a method of constructing a hair hackle in which the hair is distributed evenly on all sides of the fly as it is 30 wound around the shank of the hook.

It is frequently necessary to trim hair hackles in order to make them conform to the size of the fly to which they are applied, which trimming tends to lessen the intended similarity 35 between the artificial fly and natural insect. To eliminate this disadvantage the present invention provides a method of constructing a hackle that retains the natural tapering ends of the individual fibers of hair.

With the above and other objects in view the invention consists of certain novel details of construction and combinations of parts hereinafter 40 fully described and claimed, it being understood that various modifications may be resorted to 45 within the scope of the appended claims without departing from the spirit or sacrificing any of the advantages of the invention.

In the accompanying drawing forming part of this specification,

Figure 1 is a perspective view of a fly equipped 50 with a hair hackle constructed in accordance with the invention.

Figure 2 is a perspective view of a hair hackle 55 constructed in accordance with the invention.

Figure 3 is a side elevation of a fly showing one

of the steps of applying the hackle to the shank of the hook.

Figure 4 is a perspective view showing the weaving of the hair hackle in accordance with the invention.

Referring now to the drawing in which like characters of reference designate similar parts in the various views, as best shown in Figure 4, a silk thread 10 is looped around a fixed upright 11 and a knot 12 is tied near the loose ends. 10 The thread is then stretched tight and the loose ends gripped in the jaws of a vise 13.

Several strands of hair 14 are now grasped with the fingers of the left hand and the tip or tapering ends of the hair are laid on the flat side 15 of a small ruler, not shown, the tips of the hair being disposed to extend to any desired dimension mark on the ruler depending upon the size of the hackle to be woven. The strands of hair 14 are then gripped with a small pair of tweezers 20 15 at the point where the hair first comes in contact with the ruler. This procedure is performed with the subsequent strands of hair which are used to form the hackle and enables the operator to control the size of the hackle so that it is not 25 necessary to trim off the tip ends in order to make the hackle conform to the size of the hook 16 on which it is tied.

The entire assembly of tweezers 15 and strands of hair 14 is then held by the butt ends of the 30 hair with the fingers of one hand and then the tweezers with the tip ends of hair 14 projecting therefrom, are passed through the loop 10 of silk thread at the right of the knot 12. The tweezers 15 are then raised until the jaws thereof are flush 35 with the underside of the silk thread 10. To

perform the actual weaving step in the process, the butt 17 of the hairs is wound about the rear strand 18 of the loop and then passed forwardly 40 under both strands as shown at 19. Then the hair is passed up over the front strand 20 of the loop, as shown at 21, and then downwardly between the strands 18 and 20 as shown at 22. A half hitch 23 is then formed over both strands 18 and 20 by the hairs, and the hairs are then 45 pulled up closely and pushed against the knot 12. The half hitch prevents the hair from unraveling. The butt of the hairs is then cut off close to the strands 18 and 20 of the silk thread 50 and the tweezers removed from the tip ends of the hair. The process as above described is repeated until the desired length of hackle is produced as shown in Figure 2, each group of strands of hair being slid up closely against the imme- 55

diately preceding group and knotted to prevent the hair from slipping.

In the completed hair hackle the tip ends of the hair project in a close fringe from the silk threads 18 and 20, when the hackle is completed by severing the thread loop close to the upright and forming a knot 24 therein to tie the severed ends together.

The completed hair hackle shown in Figure 2 is then attached to the shank of the hook 16 at a point back of the eye 25 through the medium of the silk thread 10 upon which the hair hackle is woven. To apply the hackle the inner ends of the strands 18 and 20 are applied to the hook 15 shank and the hackle is wound around the hook shank near the eye 25 of the hook and securely fastened with the outer ends of the threads 18 and 20. It will be observed by referring to Figure 1 that when the hackle is wound in several 20 revolutions about the shank of the hook the hair is distributed evenly on all sides of the fly so that bunching of the hair is eliminated and life-like appearance of the fly is promoted.

In actual practice, I extensively employ other materials which are similar in appearance and texture to hair but cannot be correctly defined as hair. For instance, the Du Pont Company has recently developed a product bearing the trade name of "Nylon", which, among other uses, is 25 being used to replace bristle and hair in brushes. This product can be obtained in filaments that are no thicker than coarse hair, and my experiments reveal that hackles can be woven with it in exactly the same way that hair is used. Because of the many desirable features of "Nylon", I feel that eventually the bulk of my hackles will

be woven from this material in preference to hair. At the present time I am also employing board bristle to a certain extent, and this can not be properly classified as hair. Therefore, wherever hair is used in the specification and claims, I intend the scope of the word to include bristles, fiber or like material.

From the above description it is thought that the construction and operation of the invention will be fully understood without further explanation.

What is claimed is:

1. The method of forming a hair hackle comprising looping a silk thread upon itself to provide front and rear strands, tying the ends of the strands together with a knot, passing the tips of hair through the loop for a predetermined distance, holding the butt ends of the hairs against the underside of the loop, winding the butt ends of the hairs about the rear strands and forwardly under both strands then up over the front strand and then downwardly between the strands, then forming a half hitch over both strands by the hairs, pulling the hairs up closely and pushing the same against the knot, and cutting the butt ends of the hairs close to the strands. 20

2. In a hackle, front and rear silk thread strands, knots formed in the ends of the strands to tie the strands together, and groups of hair 30 tips of the same length knotted at the butt ends to said strands and projecting from the same side of the strands in uniform spaced relationship, said strands forming a narrow rib comparable in size to the quill of a feather hackle. 35
